FLUSH VENTILATOR

Fred N. Nelson, Seattle, Wash., assignor to Safety Boat Company, Seattle, Wash., a corporation of Washington

Application April 5, 1943, Serial No. 481,834

2 Claims. (Cl. 114—212)

This invention relates to ventilators for ships, boats and the like, and it has reference more particularly to ventilators of a type that will admit air freely in the normal use of the ventilator, and will close automatically against inflow of water in the event that spray or waves should break over the deck of a ship in rough weather; it being the principal object of this invention to provide improvements in ventilators of the kind above stated that especially adapts them for bulkhead installations and provides also for flush deck openings for inflow of the ventilating air and leaves all outside wall surfaces with which the ventilator is associated, clear and unobstructed with no projections on the deck or bulkhead.

More specifically stated, it is the object of this invention to provide a ventilator that will function effectively and efficiently in all kinds of weather, never requiring that the air inlet port be closed against inflow of water that might result from high seas, spray or waves breaking over the deck; this being by reason of the ventilator air duct being equipped with watersheds and a normally open valve that operates automatically, by water flotation to close the air outlet from the duct, and with means for the automatic draining off of the water that may enter the air duct of the ventilator.

Still further objects of the invention reside in the details of construction of ventilators for use in boats as a means to protect the engine and electrical devices, etc., against "drowning."

In accomplishing these and other objects of the invention, I have provided the improved details of construction, the preferred forms of which are illustrated in the accompanying drawings, wherein—

Fig. 1 is a sectional view, taken in a vertical plane through a ventilator embodied by the present invention.

Fig. 2 is a vertical section, taken on the line 2—2 in Fig. 1.

Fig. 3 is a horizontal section on line 3—3 in Fig. 2.

Fig. 4 is a perspective view of the float valve used in the ventilator, particularly illustrating its mounting means and the guide rods.

Fig. 5 is a sectional view showing the present ventilator as applied to a bulkhead.

Fig. 6 is a sectional detail showing means for holding the automatic valve in closed position and a closure for the air port.

Fig. 7 is a sectional view of the sealing gasket. Referring more in detail to the drawings—

In Figs. 1 and 2, 10 designates what may be the deck of a ship, and 12 designates what may be the bulkhead of a forecastle, bridge or other superstructure. In the deck, adjacent the bulkhead, is an opening 13 and this is here shown as being covered by a flush grating 14.

Leading downwardly from the opening 13 and at the inside of the bulkhead, is a watertight housing forming an air duct 15. The upper end of this housing is somewhat flared and is in direct communication with the deck opening 13. At its lower end, it communicates with a clearing port or opening 16 in the bulkhead. This water-tight housing is closed at opposite sides by the parallel side walls 17—17 and the inclined walls 17a and 17b which provide the flare at the upper end of the passage, as shown best in Fig. 2. Opposite the side of the passage that is closed by the bulkhead, the housing is closed at its upper end by an inclined wall plate 18, that extends downwardly from the deck, a vertical wall section 19 that joins with the plate 18, and an inclined lower end closure plate 20 that is welded at its top edge to the lower edge of plate 19 and to the bulkhead along its lower edge.

It is to be observed, by reference to Figs. 1 and 2, that the lower edge portions of the inclined plates 17a and 17b and the plate 18 overhang the line of their connection with the plates 17—17 and 19, respectively. Formed in the plate 19, directly beneath the overhanging portion of the plate 18, is an air port, or passage 22 opening into the space that is to be ventilated.

A horizontally disposed plate 23 is welded to the plate 19 across the top edge of the opening 22, and to the lower edge portion of the plate 18. This plate, as will presently be explained, serves to mount the upper ends of guide rods by which the automatic closure valve is mounted and guided in its travel between open and closed positions.

The port 16 which opens through the bulkhead is equipped with a valve, or closure plate 25, having its upper portion disposed inside of the housing, and its lower portion disposed at the outside of the bulkhead. This valve plate is hingedly mounted by a horizontal shaft or rod 26 that is supported inwardly offset from the bulkhead, as noted best in Figs. 1 and 3. The rod 26 is mounted at its opposite ends in brackets 27 fixed to the bulkhead, and the valve is equipped with inwardly extending ears or lugs 29 which pivot on the rod. The particular manner in which this valve plate is hingedly suspended causes it to normally assume a position closing the port 16. However,

it is adapted to be moved to an open position, as has been indicated in dotted lines in Fig. 1, for the release and outflow of any water that might wash into the lower end of the housing through the deck openings.

It will be understood, by reference to Fig. 1, that air may enter the passage or duct 15 through the grating of the deck opening, and may flow downwardly therein to pass into the ventilated space through the opening 22. However, in view of the anticipated uses of the device, and especially in view of the ventilator having its air inlet opening in a deck, which may be the top deck or outside deck of a ship or submarine, it is anticipated that at times, it may be flooded with water due to the breaking of waves across or over the deck of the ship. Therefore, it is desirable to provide means in the ventilator to prevent the flooding of the ventilated space. Small amounts of water entering the passage 15 through the grating will be diverted directly toward the lower end of the housing, and will be discharged through the valve opening 16 at the lower end of the housing to the outside of the bulkhead.

In the event that the water entering the passage is in an excessive amount, it is then desirable that some means be provided to close the air port 22, at least temporarily, so that no water will be allowed to enter the ventilated space. For this purpose, I have provided the automatic valve which is designated in its entirety by reference numeral 30 and which, in Figs. 1 and 2, is shown in its open position. This valve preferably is made of sheet metal and is of the box-like form illustrated. Also, it is adapted to move vertically from its normal open position disposed below the level of the opening 22, to a closed position overlying the opening, as seen in Fig. 6. The means for supporting the valve 30 when open and for guiding it in its travel between open and closed position comprises an angle bar 33 that is fixed horizontally to the inside of the wall plate 19 somewhat below the opening 22. Guide rods 34 and 34 are extended between the angle bar 33 and the plate 23 previously mentioned. The disposition of these two guide rods is best shown in Fig. 2, wherein it is observed that, respectively, they are disposed, close to the opposite side walls 17-17 of the air duct 15, with the float valve 30 located between them. Fixed to the opposite side walls of the valve are brackets 35 each having laterally turned feet 36 at upper and lower ends. These feet are formed with openings 37 and the guide rods are extended through the openings in the feet of corresponding brackets.

By reference more particularly to Figs. 1 and 4, it is to be observed that each guide rod is formed near its upper end with a portion 34a that is inclined toward the wall portion 19, and at a lower point it is formed with outwardly curved portions 39. The face of the valve that is adjacent the wall 19 is normally inwardly spaced from the wall for easy movement of the valve. However, when the valve is lifted by flotation in water within the housing, the ears of the mounting brackets engage with these outset portions 34a and 39 of the guide rod, thus to move the valve outwardly and tightly against the wall plate 19 across the air passage 22.

It will be understood that the automatic float valve is intended to close only when the water washes into the housing in such amounts that it cannot be immediately drained off through the port 16; for example, if the vessel should dive into

solid seas, and it is anticipated that it will open as soon as the water drains off.

It is desirable that a flexible gasket as at 40 be applied to the under face of plate 23 and to the plate 19 about the edges of the opening to seal the joint between the valve and wall when the valve is closed. Also, it is a detail of construction of the float valve that it be formed with a rather sharp ridge 30x across its top edge, flush with the outside wall of the valve so that when the valve is lifted to its closed position, it will effect a watertight seal with the gasket 40 about the opening 22.

The preferred type of gasket is that shown in Fig. 4 and Fig. 7, and comprises a strip of painted canvas 40, or the like, folded back upon itself and secured by an overlying strip 41 and rivets 42, to the wall members.

Ventilators of this particular character are especially suited for the ventilation of such war vessels as submarines and aircraft carriers, where flush deck and bulkhead openings are desirable or essential. However, it is not the intention that this type of ventilator be confined in its use to any particular kind of ship, vessel, or boat.

Furthermore, such ventilators may be made in various sizes and the air port 22 may open directly to a ventilated space, or a pipe or conduit may connect with the opening to lead to any designated space. Also, such ventilators may be used for either the supply or exhaust of air.

In Fig. 5, I have shown the adaptation of this ventilator to a bulkhead where both the air inlet and the water clearing port are in the bulkhead. In this view the upper end of the air duct 15 is formed with a cowl 45 opening through the bulkhead opening 46. Otherwise the valve is substantially like the structure already described and its corresponding parts are designated by the same reference characters.

In the event that it should be found desirable to retain the automatic valve 30 in a tightly closed position; for example, as a protection against inflow of poison gases, I have shown in Fig. 6 the valve as being equipped with a lift rod 50 passing through a guide 51 in the bottom wall 20; this rod being equipped at its lower end with a ratchet portion 52 to be engaged by a pawl 53 on a bracket 54 to hold the valve closed.

Also, in Fig. 6, I have shown the air port 22 as being equipped with a cover 55 hinged by a link 56 to adapt it to be swung between open and closed positions and to be held in either selected position by latches of any suitable kind, not herein shown.

It is anticipated that changes in the details of construction, both in the ventilator of Fig. 1 and Fig. 5 might be made, and without departing from the spirit of the invention. Therefore, it is not the desire that the claims be confined to details, but that they be given an interpretation that is commensurate with the scope of the invention disclosed.

It is the understanding that when such ventilators are applied in places that are not exposed to any material extent to the seas and weather, they need not be equipped with the float valve.

Having thus described my invention, what I claim as new therein and desire to secure by Letters Patent is:

1. In combination with a deck and a bulkhead joined with and extending down from the deck and forming a weather protected area of a ventilator for said area, comprising a housing forming a vertical air passage along the inside of the bulkhead communicating at its upper end with a deck

opening and at its lower end with a clearing port through the bulkhead; said housing having a lateral opening intermediate its ends into the protected area, an automatic valve applied to the clearing port for clearing flood water from the passage and preventing inflow of water past the valve, and a float valve in the air passage adapted to be lifted by flood water in the passage to close over the said lateral opening.

2. The combination with a bulkhead forming an enclosure for a protected area and having upper and lower outside openings therein, of a

5 housing within the protected area and applied to said bulkhead and forming an air passage connecting the upper and lower openings therein, an automatic valve in the lower opening of the bulkhead for clearing the passage of water; said housing having a lateral opening intermediate its ends into the protected area, a float valve in the passage adapted to be lifted by flood water to close over the lateral opening, and a plate overhanging the lateral opening and float valve to protect them against flood water entering the upper opening.
